HIGH TENSION INSULATOR

Application filed February 11, 1931. Serial No. 514,977.

This invention relates to high tension insulators and especially to improvements thereon whereby the formation of corona streamers and incipient sparking between the flanges of an insulator or between adjacent insulators when mounted in a string is materially reduced and in many instances entirely eliminated.

The improvement is particularly intended for application to the structure shown in my issued Patent No. 1,742,628, entitled "High tension insulator," issued January 7th, 1930, but the improvement is also applicable to other types of insulators as will hereinafter appear.

The insulator described in the above mentioned patent is designed for use in districts with a contaminated atmosphere containing dust, dirt and salts, etc., in combination with fog, dew, mist and light rains. These conditions cause a deposit to be formed on the surface of the insulators which will be partially conducting to an extent which will permit considerable leakage current to flow.

This partially conducting layer will be of the same shape as the surface of the insulators and presents an extension of comparatively high resistance of the metal electrodes and it will assume a potential corresponding to the voltage drop along this.

If the condition of the contaminating deposit is uniform throughout a string of insulators the flow of leakage current will cause a uniform potential gradient to be established along the

string and the electrical stress with respect to the air will be a maximum at the line end of the string and a minimum at the ground end. Should on the other hand the condition of the deposit be non-uniform then the potential drop along the surface will be non-uniform and may even flit from unit to unit in maximum value and cause stresses of maximum value on any unit in any position in

the string. It is therefore essential that all

units are made equally able to withstand this maximum stress.

In actual practice I have observed that if the shape of the insulators and the contaminating layer deposited thereon is such that the air becomes overstressed, corona and incipient sparking will occur. This takes place at sharply rounded edges and tends to premature sparkover between flanges and between unit and unit.

The phenomena of corona and incipient sparking of insulators in foggy weather is frequently referred to as frying and often increases to undesirable noises and causing severe interference with radio reception. I have observed that the corona streamers and incipient sparking heat up the surface of the insulating body and the contaminating layer in a multiple of streaks and spots whereby after some time the contaminating layer becomes burned or baked on the surface of the insulating body and when this takes place it is very difficult and costly to remove, eventually also injuring the glaze, which again will make dirt adhere more easily; the final result being that the insulator becomes unsuitable for its purpose due to the destroyed surface insulation.

As the result of considerable research and experimental work I have found that corona streamers and incipient sparking can be suppressed by suitably proportioning the degree of rounding or curvature on any part of the flanges, skirts, corrugations and edges of the insulator.

The object of the present invention is to generally improve and simplify the construction and operation of high tension insulators; to provide an insulator having a body portion and a plurality of projecting annular flanges; to provide an insulator which is adapted to be used singly or in string formation and particularly to round or curve the outer edges of the flanges and the ends of the insulators to such a degree as to establish a field between

adjacent flanges and units which will not be overstressed or break down the insulating value of the surrounding air thereby preventing the formation of corona streamers and incipient sparking between adjacent flanges and units.

The invention is shown by way of illustration in the accompanying drawings, in which—

10 Fig. 1 is an enlarged central, vertical section through one form of the insulator.

Fig. 2 shows a string or assembly of insulators and a conductor suspended therefrom.

15 Fig. 3 shows a standard form of insulator modified or improved according to the present invention.

Referring to the drawings in detail and particularly Figs. 1 and 2. A indicates the cross-arm of a transmission line tower or 20 pole of suitable construction; B the conductor carrying the high tension current and C a string of insulators from which the conductor is suspended. The type of insulator employed is that illustrated in Fig. 1. It consists of a head portion 2 and a petticoat or 25 skirt portion 3. This skirt portion is slightly flared or bell-shaped and its exterior surface is provided with a suitable number of superposed interspaced annular flanges or 30 petticoats 4. These petticoats are of substantially equal diameter and an exterior corrugated cylindrical surface is the apparent result.

35 The head member 2 is hollow to receive an anchor bolt 5 which is secured by a cementitious material as indicated at 6. The anchor bolt carries a link 7 and this is, in turn, connected with a metallic head member 2a which encloses the head 2 of the insulator and is 40 secured thereto by a cementitious material 8, or the like. The connections between the head members 2a and the anchor bolts 5 are preferably pivotal, as indicated at 9, and a flexible string of insulators is obtained.

45 The method of anchoring the bolts 5, the head members 2a and the manner of attaching the link 7 is of no importance and may be changed to suit varying conditions.

50 The manner of forming or shaping the annular flanges and the lower or outer edges of the insulators is of great importance and forms the subject matter of the present application. As previously stated the invention is based on the discovery that the formation 55 of corona and incipient sparking between flanges and units may be materially reduced and in many instances entirely eliminated when the outer contour of the flanges and edges are properly formed.

60 To clearly illustrate and describe this feature reference will be made to Fig. 1. In this figure it will be noted that the lower end of the insulator and the annular flanges 4 are decidedly enlarged and rounded as indicated at 10 to provide an exterior curved

surface of comparatively large radius which is free from any projections, corners, sharply rounded edges, etc.

If, for example, it is desired to design an insulator in which corona streamers, incipient sparking between flanges and between units is to be eliminated, or in other words insulators which may be operated at maximum voltage such as found at the line end of a string of insulators, the following table will 75 be a guide for a proper design.

Voltage to ground at line end of string	Min. radius of curvature
	Inches
127,000	0.50
116,000	0.45
101,000	0.40
86,500	0.32
63,500	0.23

When an insulator was constructed on this basis it was discovered that the resulting well-rounded bulb-shaped flanges and skirts were under adverse conditions able to effect a great improvement in the electrostatic field surrounding and penetrating any part of the insulating bodies on the string as a whole, avoiding undesirable concentration of the electrostatic tubes of force and thereby reducing refraction where they pass from one medium into another. This result is of great benefit when a transmission line is exposed to lightning storms.

The usual disc-shaped suspension insulator shown in Fig. 3 and used almost universally on high-voltage lines has on its underside several thin concentric corrugations or skirts with sharply rounded edges as indicated by dotted lines at 11 and 12 which during lightning storms project into the high-intensity electrostatic field between line conductor and ground, causing severe refraction of the electrostatic lines of force at the sharply rounded edges. This intensifies the formation of corona-streamers at comparatively low voltage surges and causes premature sparkover between the insulators. On the other hand when the outer edge 13 and the corrugations 14 are enlarged and rounded as indicated in full lines in Fig. 3 a great improvement will be found.

In the insulator of the present invention it becomes possible to produce large units each absorbing a greater proportion of the total voltage. This results in fewer units in a string for a given voltage whereby the voltage distribution between the units will be improved. The large unit can be produced on account of the improved electrostatic field made possible by the grading action in each unit of the well rounded bulb-shaped flanges arranged in the main electrostatic field. This action of the bulb-shaped flanges is similar to the action of shields or rings or

other forms of antennæ placed at the line end of a string of insulators in accordance with usual practice.

In insulators designed in accordance with

5 the present invention, the desired result is obtained by the rounded bulb-shaped flanges preventing premature breakdown of the air in contact with the surface of the insulating body during voltage surges.

10 It is to be understood that the radius of curvature selected for each kind of benefit secured may be the dominating one depending upon the exposure of the transmission line to atmospheric influences of various degrees of severity.

15 By these means corona and incipient sparking can be controlled and suppressed and a baking and burning on of the contaminating layer on the surface of the insulators prevented. Undesirable noises and 20 radio interference will be prevented, and finally the insulating value of the insulators can be maintained in an efficient state by the cleansing action of the natural rain, as the 25 insulating surface will not be destroyed.

While certain features of the present invention are more or less specifically described, I wish it understood that various changes may be resorted to within the scope 30 of the appended claims. Similarly that the materials and finish of the several parts employed may be such as the manufacturer may decide, or varying conditions or uses may demand.

35 Having thus described my invention, what I claim and desire to secure by Letters Patent is—

1. An insulator having a body portion, a plurality of projecting annular flanges 40 formed thereon, the outer edge of said flanges being enlarged and rounded to such a degree as to establish a field between adjacent flanges which will not be overstressed to break down the insulating value of the 45 surrounding air when subject to high potential surges.

2. An insulator having a bell-shaped body portion, a plurality of interspaced annular flanges formed on the exterior surface of the 50 body portion and extending from end to end thereof, the outer edge of said flanges being enlarged and rounded to such a degree as to establish a field between adjacent flanges which will not be overstressed to break down the insulating value of the surrounding air 55 when subject to high voltages.

3. An insulator having a bell-shaped body portion, a plurality of interspaced annular flanges formed on the exterior surface of the 60 body portion and extending from end to end thereof, the outer edge of said flanges being enlarged and rounded to such a degree as to establish a field between adjacent flanges which will not be overstressed to break down the insulating value of the surrounding air

when subject to high voltages, the lowermost of said flanges being enlarged to present a larger degree of curvature than the other flanges.

4. An insulator having a bell-shaped body portion, a plurality of interspaced annular flanges formed on the exterior surface of the body portion and extending from end to end thereof, the outer edge of said flanges being enlarged and rounded to such a degree as to establish a field between adjacent flanges which will not be overstressed to break down the insulating value of the surrounding air when subject to high voltages, the top and lowermost of said flanges being enlarged to present a larger degree of curvature than the intermediate flanges.

SVEND BARFOED.
